UNITED STATES PATENT OFFICE.

HORATIO S. JONES, OF KANSAS CITY, MISSOURI.

OPERATING-TABLE.

1,249,410.

Specification of Letters Patent. Patented Dec. 11, 1917.

Application filed January 5, 1917. Serial No. 140,732.

To all whom it may concern:

Be it known that I, HORATIO S. JONES, a citizen of the United States, residing at Kansas City, in the county of Jackson and State of Missouri, have invented a certain new and useful Improvement in Operating-Tables, of which the following is a specification.

My invention relates to improvements in operating tables.

It is particularly well adapted for physicians' or surgeons' use.

One of the objects of my invention is to provide an operating table of novel construction which will permit of a patient being disposed in many positions adapted for different examinations or operations.

A further object of my invention is the provision of novel drainage mechanism, which is convenient for use, is efficient in operation and sanitary.

Still another object of my invention is to provide novel mechanism for supporting the legs and feet of a patient in different positions.

A further object of my invention is to provide novel means for elevating and lowering the member which is adapted to support the thighs of the patient.

Another novel feature of my invention is the mechanism by which the head support is operated, which mechanism is reliable in operation and easy to operate.

Still another object of my invention is to provide novel means by which a fountain may be supported in a position for easy manipulation, and which, when the fountain is not in use, may be disposed in collapsed form out of the way of the operator.

Still another object of my invention is to provide a drainage receptacle with a cover which in the open position may be utilized as a shelf for the support of instruments and the like.

The novel features of my invention are hereinafter fully described and claimed.

In the accompanying drawings, which illustrate the preferred embodiment of my invention,

Figure 1 is a side elevation of my improved operating table with the body supporting members shown horizontally disposed.

Fig. 2 is a top view of the same.

Fig. 3 is a vertical sectional view on the

plane of the line 3—3 of Fig. 2, showing one of the foot or leg supports mounted in one of the vertical sockets of the supporting frame.

Fig. 4 is a vertical sectional view on the line 4—4 of Fig. 2.

Fig. 5 is a vertical sectional view on the line 5—5 of Fig. 1.

Fig. 6 is a vertical sectional view on the line 6—6 of Fig. 1.

Fig. 7 is a vertical sectional view on the line 7—7 of Fig. 5.

Similar reference characters designate similar parts in the different views.

1 designates a supporting frame, substantially rectangular and composed of any suitable material, principally iron or steel tubing. The frame is, preferably, provided with ball bearing casters of any usual type, and which are designated by 2.

The patient to be examined or operated upon is adapted to be supported upon five supporting members comprising a head supporting member 3, a shoulder supporting member 4, a thigh supporting member 5, a leg supporting member 6 and a foot support 7. These five supporting members are adapted to be horizontally disposed, as shown in Fig. 1, or they may each be swung from the horizontal to such position as may be best adapted for the purpose in view.

The head supporting member 3 is, preferably of sheet steel and having its forward end formed into a barrel which is pivoted on a transverse tie member 8 of the frame 1. To support the member 3 in the horizontal or other positions, it has pivoted to its underside the upper end of a toothed member 9, preferably curved, and having in its rear edge a row of ratchet teeth 10 each adapted to engage and be supported by a transverse tie rod 11 of the frame 1.

To positively swing the member 9 into or out of engagement with the rod 11, I provide a rock member 12 pivoted in a bearing 13 secured to the under side of the member 3, and provided with a crank 14 and a crank handle 15. A U shaped link 16 embraces the member 9 and has its arms pivoted to the crank 14 of the rock member 12. The crank 14 is adapted to strike and force the member 9 out of engagement with the rod 11, when the crank handle 15 is turned in a counter clockwise direction, as viewed in Fig. 4. The transverse portion of the link 110

16 is adapted to strike the forward edge of the member 9 and force said member into engagement with the rod 11 when the crank handle 15 is swung clockwise, as viewed in Fig. 4. The member 9 thus may be reliably made to engage the rod 11 without depending upon gravitation to effect this engagement.

The shoulder supporting member 4 is hinged at its forward edge upon a transverse rod 17, which forms part of the frame 1, and to which is pivoted the rear end of the thigh supporting member 5. The rear end of the member 4 in the horizontal position 15 is adapted to rest upon the member 3, as shown in Fig. 4.

For supporting the member 4 at different angles to the horizontal, I provide a U-shaped brace 18, the arms of which are pivoted to the under side of the member 4 and the transverse portion of which is provided with lateral extensions 19 which are adapted to respectively engage the teeth 20 of two longitudinally disposed bars 21 respectively secured to opposite sides of the frame 1. The teeth 20 are in the upper horizontal edges of the bars 21, so that as the member 4 is upwardly swung, the lower end of the brace 18 will pass forwardly over said teeth.

For hoisting the thigh supporting member 5, the following described mechanism may be employed.

A vertical screw 22 has a screw-threaded upper portion fitted in a vertical screw-threaded hole in the middle of a transverse bar 23 supported by the frame 1. The upper end of the screw 22 is rounded and has a bearing in a longitudinal groove 24 provided in the under side of a bearing 25 secured to the under side of the member 5. The screw 22 extends through and is rotatable in a transverse bar 26 supported by the frame 1 below the bar 23.

An inverted U-shaped member 27 has its arms secured to the upper side of the bar 26 and its transverse portion is provided with a vertical hole in which the screw 22 is rotatable and slidable.

A horizontal crank shaft 28 having an operating crank handle 29 is rotatably mounted and extends through one arm of the member 27 and a bearing 30 which is mounted upon the bar 26.

Secured to and rotatable with the crank shaft 28 is a bevel gear wheel 31 which meshes with a bevel gear wheel 32 supported on the bar 26 and splined to the screw 22 so as to rotate therewith and at the same time permit vertical movement of the screw in the gear wheel 32.

By turning the crank handle 29, the screw 22 may be turned and thereby vertically moved so as to raise and lower the thigh supporting member 5.

The thigh supporting member 5 adjacent to its forward end is provided with a drainage opening which communicates with the upper end of a drainage receptacle 33, the upper end of which is secured to the under side of the member 5. The drainage receptacle 33 at its lower end is provided with a discharge opening 34 which communicates with a discharge tube 35, the upper end of which is attached to the tubular lower end of the receptacle 33.

The tube 35 is preferably flexible, being preferably composed of soft rubber and is adapted to have its lower end detachably inserted in a tubular inlet 36 provided in a cover 37, which is removably mounted upon and is adapted to tightly close the open upper end of a receiving vessel 38, Fig. 4. The vessel 38 is, preferably, removably mounted upon a transverse horizontal plate 39, which is provided on its upper side with an annular flange 40 adapted to embrace the vessel 38.

A cover 41 is hinged to the forward end of the member 5 and is adapted to cover the upper end of the receptacle 33 and to close the opening in the member 5. The receptacle 33 is provided at its forward side with a horizontal flange 42 which, when the cover 41 is swung to the open position, shown in dotted lines in Fig. 4, horizontally supports said cover, so that the latter may be employed as a shelf for the support of instruments or other articles.

When the member 5 is to be used in the inclined position, as shown in dotted lines in Fig. 4, the tube 35 is detached from the cover 37.

The rear end of the leg supporting member 6 is rigidly secured to and is adapted to be swung by a horizontal transverse rock shaft 43, Fig. 6, which is oscillatively mounted in the frame 1 and which is provided at one end with a crank handle 44 having an outwardly extending screw-threaded arm 45 which extends through an arcuate slot 46 of a casing 47, Fig. 1, which is secured to one side of the frame 1 and within which the crank handle 44 is adapted to be swung. By turning the crank handle 44, the rock shaft 43 is turned, thereby swinging the leg supporting member 6. For releasably locking the crank handle 44 in the position to which it may be adjusted, the screw-threaded arm 45 has fitted thereon a nut 48 which is adapted to bear against the outer side of the casing 47 and which is preferably provided with a crank handle 49 to enable the nut to be easily turned.

Secured to the lower side of the foot support 7 are two downwardly and rearwardly extending bars 50, to which are respectively pivoted the forward ends of two bars 51, which are parallel with each other and with the member 6, and which have their rear

ends pivoted in the frame 1, as shown in Fig. 6. The distances between the pivotal points of the bars 51 and the member 6 are the same, so that the foot support 7 always retains a horizontal position regardless of the position of the leg supporting member 6.

The bars 51 are bracing bars which serve as bracing means, through the intermediacy of the bars 50 and foot support 7 for supporting the outer end of the leg supporting member 6.

By loosening the crank nut 48, the crank handle 44 may be turned to any desired position and then locked in such position by 15 tightening the crank nut 48, thereby swinging the member 6 and foot support 7 to and holding them in any desired position.

Respectively secured to opposite sides of the frame 1 are two upwardly and forwardly inclined tubes 52 in which are respectively slidably and detachably mounted two foot or leg supporting members 53, each of which is provided at its upper end with a ring 54 adapted to support a foot or to receive therethrough a leg of a patient who is supported upon the operating table.

The upper side of each of the tubes 52 is provided with a screw-threaded hole in which is fitted a crank screw 55, Fig. 7, 30 which is adapted to enter any one of a series of notches 56 with which the upper edge of the adjacent leg supporting member 53 is provided. By properly adjusting the screw 55, the adjacent leg supporting member 53 35 may be withdrawn or moved to any desired position.

The frame 1 is provided at opposite sides respectively, adjacent to its forward end and upper side with two sockets 57, which are 40 closed at their lower ends and which are adapted to receive and support in a vertical position the lower ends of the members 53, when the latter are removed from the tubes 52, as shown in dotted lines in Figs. 1 and 45 7. In the last named position, the rings 54 are adapted to receive therethrough and to support in an elevated position the legs of the patient.

For the purpose of supporting a fountain 50 to be used in connection with the drainage receptacle 33, I provide a fountain support consisting of the following described parts. The fountain support is, preferably, extensible and comprises two sections, one of which 55 is pivoted to the frame 1 and the other of which is longitudinally adjustable on the pivoted section. The pivoted section comprises a tubular member 58, one end of which has a serrated side face adapted to be 60 releasably clamped to a similarly serrated or corrugated side face of a member 59 which is secured to the frame 1, Figs. 1 and 2. Extending through the members 58 and 59 is a thumb screw 60 upon the outer end of which 65 is fitted a nut 61 which is adapted to bear

against the member 58. The thumb screw 60 is horizontal and transversely disposed, so that when loosened, the member 58 may be swung from the horizontal position shown in Fig. 1 to a vertical position or to any intermediate position and then retained in such position by tightening the thumb screw 60.

Slidably mounted in the member 58 is a rod 62 which is adapted to be secured in any position to which it is adjusted by a 75 thumb set screw 63 mounted in the member 68. The outer end of the rod 62 is provided with a hook 64 which is adapted to support any ordinary type of fountain, not shown. When not in use, the fountain support may 80 be swung to the longitudinal horizontal position shown in Fig. 4.

From the foregoing description it will be understood that the various movable supporting members of my improved operating 85 table may be adjusted to a variety of positions such as may be best adapted for the particular purpose in view.

I do not limit my invention to the structure shown and described, as modifications, 90 within the scope of the appended claims, may be made without departing from the spirit of my invention.

What I claim is:—

1. In an operating table, a supporting 95 frame, and a thigh supporting member hinged thereto so as to be swung upon its rear end to and from a horizontal position and provided with a drainage opening adjacent to its free end, and provided with a 100 cover adapted to be swung from its position closing said opening to an open horizontal position, and in the latter position serving as a shelf.

2. In an operating table, a supporting 105 frame, a thigh supporting member hinged thereto at its rear end so as to be swung to and from a horizontal position and provided adjacent to its free end with a drainage opening and having a cover movable 110 from a position closing said opening to an open horizontal position in which it will serve as a shelf, and a drainage receptacle carried by said thigh supporting member and communicating at its upper end with 115 said opening.

3. In an operating table, a supporting frame, a head supporting member having its forward end pivoted thereto, a toothed member pivoted to said head supporting 120 member, and adapted to have its teeth releasably engage said supporting frame for holding the head supporting member in different positions, a rock member pivoted to said head supporting member and provided 125 with a crank and a crank handle, the crank being adapted to engage said toothed member so as to swing the latter out of engagement with the supporting frame, and a link carried by said crank and adapted to engage 130

said toothed member so as to swing the latter into engagement with said supporting frame.

4. In an operating table, a supporting frame, a head supporting member pivoted thereto, a toothed member pivoted to said head supporting member and adapted to support the latter in different positions, a rock member pivoted to said head supporting member and provided with a crank adapted to engage the toothed member and swing the latter out of engagement with said frame and a U-shaped link having its arms carried by said crank and having its transverse portion adapted to engage said toothed member so as to swing the latter into engagement with said frame.

5. In an operating table, a supporting frame, a shoulder supporting member, a head supporting member, a thigh supporting member, a leg supporting member, said members each being pivoted to the frame so as to swing from a horizontal position, the shoulder and head supporting members being pivoted at their forward ends, and the thigh and leg supporting members being pivoted at their rear ends, and means for releasably retaining said members in different positions with respect to the horizontal and independently of each other.

6. In an operating table, a supporting frame, a thigh supporting member hinged thereto and having a drainage opening, a drainage receptacle secured to the under side

of said member and communicating with said opening and having at its lower end a discharge tube, and a receiving vessel supported by said frame and having a removable cover having an inlet adapted to receive the material discharged from said tube when the thigh supporting member is in a pre-determined position.

7. In an operating table, a supporting frame, a thigh supporting member hinged thereto and having a drainage opening, a drainage receptacle carried by said member and communicating with said opening and having at its lower end a discharge tube, and a receiving vessel having a removable cover provided with an inlet tube adapted to be detachably connected with said discharge tube when the supporting member is in a pre-determined position.

8. In an operating table, a supporting frame having two vertical sockets respectively at opposite sides thereof, two upwardly and forwardly inclined tubes secured to the supporting frame at opposite sides thereof respectively, and two foot or leg supporting members respectively slidably adjustable to different positions in said tubes, and removable therefrom and adapted to be respectively mounted in said sockets so as to respectively support the legs of a patient.

In testimony whereof I have signed my name to this specification.

HORATIO S. JONES.

Copies of this patent may be obtained for five cents each, by addressing the "Commissioner of Patents, Washington, D. C."
